United States Patent Office.

JAMES G. KENYON, OF PROVIDENCE, RHODE ISLAND.

Letters Patent No. 90,948, dated June 8, 1869.

IMPROVEMENT IN STUDS.

The Schedule referred to in these Letters Patent and making part of the same.

To all whom it may concern:

Be it known that I, JAMES G. KENYON, of the city and county of Providence, in the State of Rhode Island, have invented a new and useful Improvement in Shirt-Studs; and I do hereby declare that the following is a full, clear, and exact description of the same, reference being had to the annexed drawings, making a part of this specification, in which—

Figure 1 represents a side view of my invention as locked together when in use.

Figures 2 and 3 are views of the top; the one, a side view; the other, a view of the under surface.

Figures 4 and 5 are views of the bottom part; the one a side, and the other a sectional view.

Figures 6, 7, 8, and 9, are detailed parts.

In the accompanying drawings, fig. 1 represents a shirt-stud or button, well known as an article of jewelry, A representing the post of the top, as shown on fig. 2, and B, the tubular post or socket of the bottom, as shown on fig. 4.

To enable others skilled in the art to make and use my invention, I will proceed to describe its construction and operation.

The post A, fig. 2, being the proper size to fit the tube or socket B, I make, on its side, a groove or channel, called the main channel, having its entrance or mouth at the end, fig. 3. A suitable distance from this end, running from the main channel, fig. 2, I make a side channel, which side channel is cut concentric with the centre of A. A recess is made at the end of this side channel, for the purpose of locking A and B together.

The tube or socket B is provided with a projection or pin, e, on its inner surface, as shown on section, fig. 5. This pin is made so that it can pass easily along in the main channel of A, and be turned into the recess at the end of the side channel.

A plate, with one or more small points, and a hole

through its centre, is soldered or attached to one end of socket B, fig. 7.

C, fig. 6, represents a round piece of sheet-metal raised in a die. The upper surface is made convex, fig. 8; the under, concave, which I use as a spring.

Fig. 9 represents a cap, for holding the spring C, and to be attached to the plate on B, as shown on section, fig. 5.

The spring C, being placed in the cap, and the cap soldered or burnished to the plate, forms one part of the stud, as shown by fig. 4.

To use my invention, socket B is passed through an eyelet or button-hole of a shirt, from the under side. The post A of the top is then pressed and turned into the socket B, (B being held from turning by the points on the plate, these points entering the fabric.) The pin e enters the main channel on A. The end of post A brings up against the spherical spring C, and, by a little pressure, the centre is depressed, so that the pin e can be turned into the side channel, and, by the reaction of the spring, forced into the recess, thus securing and locking the two parts together. To remove the same, press the top, and turn the opposite direction.

The same principle could be made by forming the channel in socket B, and making a pin on A, to slide into this channel.

What I claim as my invention, and desire to secure by Letters Patent of the United States, is—

The improved shirt-stud herein described, consisting of the front, A, with its slotted shank, the hollow back, C, provided with a spring, and the back shank B, the whole arranged and operating substantially as described, for the purposes specified.

JAMES G. KENYON.
